UNITED STATES PATENT OFFICE.

SIDNEY D. HOY, OF SIOUX CITY, IOWA.

PORTRABLE CONCRETE-MIXER.

1,186,401.

Specification of Letters Patent.

Patented June 6, 1916.

Application filed April 1, 1913. Serial No. 758,231.

To all whom it may concern:

Be it known that I, SIDNEY D. HOY, a citizen of the United States, residing at Sioux City, in the county of Woodbury and State 5 of Iowa, have invented new and useful Improvements in Portable Concrete-Mixers, of which the following is a specification.

This invention relates to improvements in concrete mixers and it proposes a portable 10 concrete mixer which is especially designed for local or domestic use, *e. g.* for use in the preparation of relatively small batches of concrete, such as may be frequently required on a farm in connection with the construction 15 of out buildings, the erection of fences or porches, the installation of hydraulic rams, and various other operations of every day occurrence in the up keep of a modern farm.

20 The objects of the invention are to provide a concrete mixer which shall be of inexpensive construction, and of strong and durable character, involving no parts of delicate nature or which are readily liable to 25 breakage or injury; which shall be very light in weight and as readily portable as an ordinary wheel-barrow; which may be operated with ease and facility, as regards both the mixing of the batch and the discharge 30 thereof; which shall thoroughly and rapidly mix the ingredients of the concrete; and in which the operating parts are compactly arranged and accessibly located.

An embodiment of the invention is illustrated in the accompanying drawings, wherein:

Figure 1 is a vertical central sectional view of a portable concrete mixer in which the features of the invention are incorporated; 40 Fig. 2 is a side elevation thereof, showing the mixing barrel in a position at right angles to the position it occupies in Fig. 1; Fig. 3 is a front elevation thereof, partly in section, to show the details of the end closure of the mixing barrel; Fig. 4 is a detail front elevation showing the disengaged position of the pawls or detents which are provided to hold the mixing barrel against movement when the machine is being wheeled 45 from one point to another; Fig. 5 is a detail sectional view of the end closure shown in Fig. 3, but showing a partly open relation thereof.

Similar characters of reference designate

corresponding parts throughout the several 55 views.

The mixing operation is accomplished by means of a rotatable barrel 1 which preferably has an oval cross section and has its axis of rotation centrally located and coincident with its smallest diameter. The barrel 1 rotates on a stationary shaft 2 and carries a bearing sleeve 3 which surrounds said shaft and extends transversely through said barrel.

60 The objects of the invention are served by organizing the machine along the general plan of a wheel-barrow, the mixing barrel being arranged in relation to a cradle or frame which takes the place of the body of 70 the ordinary barrow, and furnishes an immovable support for the barrel during the concrete mixing operation. The cradle or frame which supports the mixing barrel 1 is preferably made in one piece, excepting, 75 of course, certain braces and stays. The material used may be ordinary piping which is fashioned to provide two U-shaped side standards 4, an arch-shaped member 5 extending between the upper front ends of 80 said standards, and handles 6 projecting rearwardly from the upper rear ends of said standards. Cross bars 7 and 8, arranged at the same elevation, connect the standards 4 at their upper front and rear ends; the 85 cross bar 7 being located in a vertical plane coincident with the member 5. The bars 7 and 8 furnish support for the shaft 2 and are provided with centrally arranged bearings or brackets in which the ends of said 90 shaft are held.

95 The front bars of the standards 4 furnish support for a forwardly projecting yoke 9 and the ground wheel 10 is arranged between the side bars of the yoke, the latter having bearings for the axle or hub spindle of said wheel. The yoke 9 is reinforced by braces 11 which connect the side bars thereof and the front bars of the standards 4.

The rotation of the barrel 1 is effected by 100 suitable gearing which conveniently comprises a relatively large spur wheel 12 fast on the sleeve 3, and a relatively small pinion 13 arranged above the spur wheel 12 and having its shaft journaled in a strap 14 105 secured to the side bars of the member 5 and provided with a crank handle 15.

Suitable provision is made for preventing

rotation or turning movement of the mixing barrel when the machine is being wheeled from place to place. As shown in Figs. 3 and 4, detents 16 are pivoted to the 5 sides of the member 5 and are connected by links 17 to a lever 18 which is pivoted at one end thereof to the cross bar 7. Adjacent the free end of said lever the frame carries a lug 19 upon which the lever is supported, 10 as shown in Fig. 4, during the mixing operation. When the lever 18 rests on the lug 19, the detents 16 are disengaged from the wheel 12 with which they coact, and the gearing for rotating the barrel 1 may be 15 freely operated. When the mixing operation has been completed, or when it is desired to arrest the rotation of the barrel 1, the lever 18 is disengaged from the lug 19 and dropped to the position shown in Fig. 20 3, at which time the detents 16 engage the teeth of the wheel 12. It will be understood that the lever 18 has some loose play about its pivot pin, and consequently, that it may be moved laterally through a slight range 25 and thereby readily engaged with and disengaged from the lug 19.

As already stated, the machine effects a rapid and thorough mixing of the ingredients of the concrete. This rapidity and 30 thoroughness of action is due, in part, to the cross sectional outline of the barrel 1 and the selection of the axis 2 in relation thereto, and in part to the provision of baffles 20, consisting, in the instance 35 closed, of transversely extending bars arranged in upper and lower series and adjacent the ends of said barrel. As the barrel is rotated, the material is rapidly, violently, and as a body or in bulk, overturned, and 40 thrown from one end of the barrel to the other. During this movement of the material in the longitudinal plane of the barrel, the baffles 20 act to thoroughly and continuously divide or break up the shifting mass, 45 and the action of these baffles is rendered the more efficient since the oval cross sectional shape of the barrel assures of substantial, and violent or forcible shifting movements of the material as a mass. 50 The ingredients to be mixed may be conveniently introduced into the barrel 1 through an elongated opening in the curved wall thereof, which opening is normally closed by a suitable lid 21, preferably having a hinged mounting, and positively held 55 in closed position by a suitably constructed sliding bolt 22.

The end walls of the barrel 1 are preferably flat and may be conveniently utilized 60 in connection with the discharge of the concrete after the mixing operation. The end walls are provided with relatively large openings 23, which extend from the curved wall of said barrel through nearly 65 half of the length of the flat walls, and are

located in relation to one of the longitudinal nodal portions of the barrel. Each of the end walls of the barrel is provided with a discharge opening 23, in order that the contents of the barrel may be discharged at 70 either side of the machine, in accordance with the dictates of convenience. The discharge of material from the barrel is effected by tilting the barrel in either direction to a position mid-way between the position of Figs. 2 and 3, locking the barrel against rotation, from the position to which it is tilted, and uncovering the lower of the openings 23. The nodal portion of the barrel 1, in relation to which said openings 80 are arranged, will obviously function as an inclined chute and discharge the material through the lower uncovered opening 23.

The openings 23 are controlled by slides 85 24, the edge portions of which engage in guide members 25 extending longitudinally of the end walls of the barrel, and which hold said slides in relation to said end walls. Each slide 24 may be conveniently operated by a lever 26, which is pivoted to the end wall upon which the slide is arranged and is connected to the slide by a link 27. In the closed position of the slides, the lever 26 and the link 27 lie adjacent one another in parallel relation, and in positions of dead center. To open the slide, the lever 26 is moved from the position shown in Fig. 3 to a position in which it is in line with the link 27, and projects beyond the end wall 95 of the mixing barrel. At such time the 100 slide will be held in open position. Fig. 5 shows a slide 24 in partially open position.

The standards 4 are suitably braced and connected, and at their rear sides are preferably equipped with L-shaped members 4^a 105 which, when the machine is at rest, engage the ground as supports and insure that the machine has suitable stability during the mixing operation.

It will be apparent that the machine may 110 be economically manufactured; that it embodies no parts which are liable to breakage or derangement; that the parts which it embodies are compactly organized and are readily accessible; that on account of its lightness it may be readily wheeled from place to place; that it accomplishes the mixing of the concrete ingredients readily and thoroughly; and that it provides for the discharge of the mixed ingredients in 115 a facile manner and from either end of the barrel.

Having fully described my invention, I claim:

In a concrete mixer, a frame, a mixing 125 barrel supported thereby for operative rotation on a fixed horizontal axis in a vertical plane, having a central longitudinal trough-like nodal portion extending uniformly throughout its length constantly in 130

the plane of its rotation and having end walls provided with discharge openings which extend to said nodal portion and are located at the same side of said axis, and 5 movable closures for said openings, the mixing barrel being movable about its axis of rotation to an inclined position wherein its nodal portion may function as a chute to effect the discharge of material from

either end of said barrel in accordance with 10 the direction of inclination thereof.

In testimony whereof I have hereunto set my hand in presence of two subscribing witnesses.

SIDNEY D. HOY.
